CLAIM

The ornamental design for a flow channel plate of a cartridge for medical testing equipment, as shown and described.

DESCRIPTION

FIG. 1 is a front view of a first embodiment of a flow channel plate of a cartridge for medical testing equipment showing our new design;

FIG. 2 is a top plan view thereof;

FIG. 3 is a right side view thereof;

FIG. 4 is an enlarged view of the portion defined by crop lines 4-4 in FIG. 1;

FIG. 5 is another enlarged view similar to FIG. 4 in which section lines 6-6 are shown;

FIG. 6 is a cross-sectional view thereof taken along lines 6-6 in FIG. 5;

FIG. 7 is a front view of a second embodiment of a flow channel plate of a cartridge for medical testing equipment showing our new design;

FIG. 8 is a top plan view thereof;

FIG. 9 is a right side view thereof;

FIG. 10 is an enlarged view of the portion defined by crop lines 10-10 in FIG. 7;

FIG. 11 is another enlarged view similar to FIG. 10 in which section lines 12-12 are shown;

FIG. 12 is a cross-sectional view thereof taken along lines 12-12 in FIG. 11;

FIG. 13 is a front view of a third embodiment of a flow channel plate of a cartridge for medical testing equipment showing our new design;

FIG. 14 is a top plan view thereof;

FIG. 15 is a right side view thereof;

FIG. 16 is an enlarged view of the portion defined by crop lines 16-16 in FIG. 13;

10

4

10

FIG. 17 is another enlarged view similar to FIG. 16 in which section lines 18-18 are shown; and, FIG. 18 is a cross-sectional view thereof taken along lines 18-18 in FIG. 17.

The broken lines illustrate portions of the flow channel plate of a cartridge for medical testing equipment and form no part of the claimed design. The dash-dotted lines denote the boundary of the claim and form no part of the claimed design. The dashed double-dotted lines in FIGS. 5, 11, and 17 denote the cross-section lines.
